UNITED STATES PATENT OFFICE.

GEORGE THOMAS COOKE, OF NEW YORK, N. Y.

END REENFORCEMENT FOR RAILWAY CARS.

Application filed June 6, 1924. Serial No. 718,285.

A great many wooden frame box cars are in service, the end framing of which consists of wooden end plate, end sills, corner post, end post and diagonal braces, which wooden end framing is sheathed on the outside and lined on the inside with wooden planking. Such wooden constructed cars are not strong enough to meet present railroad operating conditions.

10 The modern classification hump, heavy locomotive, emergency air brake and other operating conditions break the lading away from its moorings and throw it violently against the end of the car, breaking the end framing described above. This framing fails by the wooden end plate breaking in its middle, or (2) breaking adjacent the top of the end post where it is weakened by the hole for the vertical tie rod; (3) by the breaking 20 of the attachments securing the end plate to the side plate; (4) by the end post breaking between its extremities; (5) by the end post breaking away from the end plate at its top, or (6) by the end post breaking away from 25 the end sill at its bottom.

One of the objects of my invention is to provide means to reenforce the framing of an old wooden box car to prevent the failures mentioned hereinbefore.

30 Another object of the invention is to provide such a reenforcement so that it can be applied to the end sill, end plate and corner post without removing such parts from the car.

35 Another object of the invention is to provide means for attaching a diagonal bracing to such reenforcement or stiffener to transmit the thrust imposed on the end lining back to the side plates of the car, thus relieving the wooden end plate of these 40 stresses. Such diagonal braces are old in themselves, but my invention consists in part of providing an element which reenforces the wooden end plate and also provides 45 means of readily attaching a diagonal bracing and the end posts to it.

Another object of the invention is to retard the lateral weaving of the car which tends to distort the car thereby causing 50 leaks. This lateral weaving is caused by uneven track, unbalanced lading, etc.

In the drawings:

Fig. 1 is an end elevation of a car with one form of my invention applied thereon.

55 Fig. 2 is a section along line 2—2 of Fig. 1.

Fig. 3 is a fragmentary view of a freight

car with my invention applied thereon wherein the roof and running boards of the car are removed.

In the drawings the end sill 1; end plate 2; end post 19; corner post 4; diagonal bracing 5; and lining 7 constitute the end framing referred to. The side framing is partially shown by side sills 8; side plates 9 and side lining 10.

60 The end plate stiffener is a rolled or pressed Z-bar 11 having a vertical portion positioned on the inside of the end plate 2 and secured thereto by bolts 12. This vertical portion is provided with flange 33 70 which extends back and is secured to the inside of the side plate 9 by bolts 13.

75 The Z-bar stiffener 11 has an upper flange 14 to which the diagonal bracing members 15 and 16 are secured. These diagonal braces 15 and 16 are secured to the Z-bar 11 adjacent the tops of metallic end post 19 and extend back toward the middle of the car and are secured to the side plates 9 by bolts 17. The drawings show a cross diagonal bracing, however, any form of bracing 80 may be used and still come within the scope of this invention.

85 The Z-bar stiffener 11 is provided with a lower horizontal flange 18 to which the metallic end post 19 is secured. Wooden nailing strips 20 are secured to this end post 19 to which the lining 7 is nailed. This flange 18 is provided at its opposite ends with flanges 30 which are secured to the corner post 4 by bolts 21. An outside sheathing may or may not be applied as desired.

90 The end sill 1 is reenforced by a pressed or rolled Z-bar reenforcing member 22 which 95 is provided with a downwardly extending flange 23 secured to the end sill 1 by bolts 24. The Z-bar reenforcement 22 has an upwardly extending inner flange 25 to which the metallic end post 19 is secured by connecting angles 26 and 27. The horizontal web is provided with upwardly extending flanges 29 at its opposite extremities which are secured to the corner post 4 by bolts 28.

100 The vertical flange 23 of the lower Z-bar 105 is provided with flanges 31 at its opposite ends which extend back and are secured to the outer face of the side sill 8 by bolts 34.

110 The flanges 29 of the lower Z-bar reenforcement and the flanges 30 of the upper Z-bar stiffener brace the end framing against the lateral weaving of the car.

In repairing old wooden cars it is found necessary to replace the sheathing because it has rotted and to replace the lining because it has been broken to pieces by the shifting lading. In applying my device to an old car the sheathing, lining, end post and end braces are removed; the upper Z-bar 11, lower Z-bar 22 and the end post reinforcements 19 are all riveted together in the shop. The diagonal braces 15 and 16 and their gusset member 32 are also riveted together in the shop. These assembled parts are brought to the car and installed as units. The end nailing strips 20 and diagonal braces 5 are then installed and the lining 7 is nailed thereto and the car is completed. It is readily seen that this is a very simple and economical process.

I claim:

- 20 1. In a railway car, the combination of end posts, corner posts, side sills, an end sill, and a Z-shaped reenforcing member having a horizontal web secured to said end sill and said end posts, a rear vertical flange secured to said end posts, a front vertical

flange secured to said end sill and provided with flanges secured to said side sills.

2. In a railway car, the combination of end posts, corner posts, side sills, an end sill, and a Z-shaped reenforcing member having a horizontal web secured to said end sill and said end posts and provided with flanges secured to said corner posts, a rear vertical flange secured to said end posts, and a front vertical flange secured to said end sill and provided with flanges secured to said side sills.

3. In a railway car having side plates, side sills, corner posts, end posts, an end sill, and an end plate, the combination of a diagonal bracing, a Z-shaped stiffening member and a Z-shaped reenforcing member; said stiffening member secured to said end plate, side plates, end posts, corner posts and diagonal bracing, said reenforcing member secured to said end sill, side sills, end posts, and corner posts, the opposite ends of said bracing secured to said side plates.

GEORGE THOMAS COOKE.
